UNITED STATES PATENT OFFICE.

LINDSAY B. FRIE AND ELMER G. BERGMANN, OF ST. LOUIS, MISSOURI.

SHORT-CIRCUITING SWITCH.

Application filed February 2, 1928. Serial No. 251,262.

Our invention relates to a short-circuiting switch and particularly to an oil filled switch adapted for cutting transformers out of circuit. One object of our invention is to produce a switch which will be simple in construction, easy of manipulation and in which the parts are easily renewable. Another object of our invention is to so construct the switch that it will be completely waterproof. 10 In the accompanying drawings which illustrate one form of switch made in accordance with our invention; Figure 1 is a vertical central section; Figure 2 is an enlarged section of one of the inlet connections; Figure 3 is a 15 detached view of the short-circuiting rod; Figure 4 is a top plan view; and Figure 5 is a diagrammatic view showing the switch in connection with a set of transformers which it is adapted to short circuit.

20 The casing 1, which is circular in cross section and preferably tapered longitudinally, may be of cast iron or other suitable material formed in the lower end of the casing is a threaded opening to receive a threaded plug 2, preferably of brass, which is slightly tapered to form an oil tight joint. Carried by the plug 2 is a downwardly projecting stem 3 adapted to be connected with the grooved wire and an upwardly extending stem 4 provided with an opening to receive the lower end of the short-circuiting rod. Secured to the upper end of the casing by bolts 5 is a cover plate 6 having interposed between it and the casing an insulating block 7. Formed in the cover plate is an opening surrounded by a threaded flange 8 to engage a screw cap 9. Surrounding the stem 4 is the lower end of a perforated tube 10. This tube is formed of material such as 25 mica composition, which not only serves as an electrical insulation but is also heat resisting. The upper end of the tube surrounds a stem 11 having an enlargement or head 12 set into the insulating block 7. Extending through 30 the stem 11 and head 12 is a bore 22 for the passage of the short-circuiting rod and the insulating block 7 also has an aligning opening for this purpose. In the head at diametrically opposite sides are openings to receive the inlet and outlet supply wires 13 which are secured in position by set screws 14. In order to hold the wire sockets in alignment the head is made square, as shown, or of other non-circular form. Formed on opposite 35 sides of the casing are nipples 15 extending

downwardly at an angle and adapted to be connected by union nuts 16 with the terminal thimbles 17 of the line wire. In the nipples 15 are sleeves 18 of material similar to the tube 10. These sleeves not only serve to insulate the wires 13 from the nipples but by extending up to a point near the top of the casing enable the casing to be filled with oil to level indicated by the broken line A—A in Figure 1, without allowing the oil to drain off when the connections are changed. In Figure 2 we have shown the line leading from the head 12 provided with a socket 19 and the main line with a split plug 20. In the connection at the opposite side these parts will be reversed, the socket being on the main line and the plug on the wire leading to the head. The short-circuiting rod 21, of copper or other good conducting material, is of the proper diameter 40 to fit snugly in the bore 22 and the opening in the stem 4. It is provided with an insulating handle 23 by means of which it may be inserted, after removal of the screw cap 9, as shown in dotted lines in Figure 1 to 45 connect the line wire with a ground wire 24 connected to the stem 3.

It will be evident that while our switch is of the simplest construction it is completely waterproof and easy of use. Further, while the construction is such that the parts are not likely to be injured in use it is possible, in case such injury does occur, to remove and replace any of the parts easily.

Having described our invention, what we claim as new and desire to secure by Letters Patent of the United States is:

1. In a device of the class described, the combination with a casing adapted to contain oil, of a conducting stem carried in the lower end of said casing, a perforated tube of insulating material surrounding said stem, an insulating cover for said casing, a contact block engaging with said tube and held against said cover thereby, a pair of lateral inlets carrying line wires connected to said block, and a short-circuiting rod adapted to connect said contact block and stem. 95

2. In a device of the class described, the combination with a casing adapted to contain oil, of a screw threaded plug in the lower end of said casing provided with a conducting stem, a perforated tube of insulating material surrounding said stem, an insulating cover for said casing provided in its 100 105 110

- lower face with a recess, a contact block held in said recess by said tube, and a short-circuiting rod adapted to pass through said contact block and engage with said stem.
5. 3. In a device of the class described, the combination with a casing adapted to contain oil, of a screw threaded plug in the lower end of said casing provided with a conducting stem, a perforated tube of insulating material surrounding said stem, an insulating cover for said casing provided in its lower face with a recess, a contact block held in said recess by said tube, a short-circuiting rod adapted to pass through said contact block and engage with said stem, and a removable cap to cover the end of said rod.
4. In a device of the class described, the combination with a casing adapted to contain oil, of a screw threaded plug in the lower end of said casing provided with a conducting stem, a perforated tube of insulating material surrounding said stem, an insulating cover for said casing provided in its lower face with a recess, a contact block held in said recess by said tube, a short-circuiting rod adapted to pass through said contact block and engage with said stem, a cover plate over said insulating cover, and a screw cap carried by said insulating plate to cover the end of said rod.
5. In a device of the class described, the combination with a casing adapted to contain oil and provided with lateral nipples, a contact member in the lower end of said casing, a second contact member in the upper part of said casing, a perforated insulating tube extending between said contact members, a short-circuiting rod extending through said tube and connecting said contact members, line wires passing through said nipples and connected to said upper contact member, and insulating tubes carried by said nipples, said tube surrounding said line

wires and terminating adjacent to said upper contact member.

6. In a device of the class described, the combination with a casing adapted to contain oil and provided with lateral nipples, a contact member in the lower end of said casing, a second contact member in the upper part of said casing, a perforated insulating tube extending between said contact members, a short-circuiting rod extending through said tube and connecting said contact members, line wires passing through said nipples and connected to said upper contact member, and upwardly inclined insulating tubes carried by said nipples, said tubes surrounding said line wires and terminating adjacent to said upper contact member.

7. In a device of the class described, the combination with a casing adapted to contain oil and provided with downwardly inclined lateral nipples, of a screw threaded plug in the lower end of said casing provided with a conducting stem, a perforated insulating tube surrounding said stem, an insulating cover for said casing provided in its lower face with a recess, a contact block held in said recess by said tube, a short-circuiting rod extending through said tube and connecting said contact block and stem, a cover plate over said insulating cover, a screw cap carried by said cover plate to cover the end of said rod, line wires passing through said nipples and connected to said contact block, and upwardly extending insulating tubes carried by said nipples, said tubes surrounding said line wires and terminating adjacent to said contact block.

In testimony whereof, we hereunto affix our signatures, this 31st day of January, 1928.

LINDSAY B. FRIE.
ELMER G. BERGMANN.
